ELECTRICAL APPARATUS

Bernard E. O'Hagan, Swissvale, Pa., assignor to
The Union Switch & Signal Company, Swiss-
vale, Pa., a corporation of Pennsylvania

Application November 13, 1929, Serial No. 406,883
Renewed January 11, 1936

28 Claims. (Cl. 246—135)

My invention relates to electrical apparatus, and particularly to apparatus for controlling an electric motor, such as a railway switch operating motor or the like, from a remote point.

5 I will describe one form of apparatus embodying my invention, and will then point out the novel features thereof in claims.

10 The accompanying drawing is a diagrammatic view illustrating one form of apparatus embodying my invention.

15 Referring to the drawing, the reference character A designates a railway traffic controlling device here shown as a track switch of the usual form operated, through any suitable form of mechanism, by a motor M comprising an armature 1 and a field 2. Associated with the switch A is a circuit controller, designated by the reference character E, and comprising a contact 3—5 which is closed at all times except when the switch 20 occupies its full normal position, in which it is illustrated in the drawing, and a contact 3—4 which is closed at all times except when the switch occupies its full reverse position. The switch A also operates a pole-changer designated by the 25 reference character H.

The motor M is controlled jointly by a polarized relay F which may be located adjacent the switch, and by a manually operable lever L which may be one of a number of such levers in an interlocking 30 machine located at a point remote from the switch, such for example as in an interlocking cabin. Lever L is capable of assuming a plurality of different positions indicated by broken lines in the drawing and designated by the reference 35 characters N, B, D and R. Associated with the lever L are a plurality of contacts adjacent each of which is a letter or letters which correspond to the lever positions for which the corresponding contact is closed. For example, contact 13^a is 40 closed only when the lever L is in the B position. Similarly, contact 63^a is closed when lever L is in the R position, the D position, or any position intermediate these two. Also associated with the lever L is a contact 66^a which is closed when the 45 lever L is intermediate the B or D positions, but which is opened when the lever occupies its B or D positions, or any position between its N and B or D and R positions.

Attached to the lever L is a locking segment 6 50 co-operating with a latch 7 operated by a magnet 8. As shown in the drawing, the lever is in the N position. If the operator attempts to move the lever towards the R position, a projection 6^a on the underside of the segment 6 will engage the 55 latch 7 and prevent movement of the lever to the

D position unless the magnet 8 is de-energized. If the magnet 8 is de-energized to permit the projection 6^a to pass the latch 7, the magnet must be subsequently energized to lift the latch out of engagement with the shoulder 6^b to permit the 5 lever to be moved to the full reverse position. In similar manner, when the lever is moved from the R to the N position, the magnet 8 must be de-energized to permit the projection 6^a to pass the latch 7 to allow the lever to assume the B position, and must again be energized to permit the shoulder 6^c to pass the latch 7 to allow the lever to move to its normal position.

The magnet 8 is provided with two circuits 15 which are controlled by the usual polarized indication relay K and by contacts on the lever L. When relay K is energized in the normal direction, so that its polar contacts are swung to the left, the first circuit for magnet 8 is closed provided lever L is in the B position, and current 20 flows from one terminal X of a suitable source of current not shown in the drawing through wire 9, front contact 10 of relay K, wire 11, normal contact 12—12^a of relay K, wire 13, contact 13^a of lever L, wire 14, winding of magnet 8, 25 and wire 15, back to the other terminal Y of the source. When relay K is energized in the reverse direction, so that its polar contacts are swung to the right, however, the second circuit for magnet 8 is closed provided lever L is in the 30 D position, this circuit passing from terminal X, through wire 9, front contact 10 of relay K, wire 11, reverse contact 12—12^b of relay K, wire 16, contact 16^a of lever L, wires 17 and 14, winding of magnet 8, and wire 15 to terminal Y. 35

Relay K is supplied with current over the same line wires which supply current to the motor M, and this supply is controlled by contacts on the lever L and by the pole-changer H in such manner that this relay will always indicate the position of the switch, regardless of the position of the lever, as will be explained hereinafter.

As shown in the drawing, switch A occupies its normal position. Contact 3—4 of circuit controller E and contacts 44—44^a and 55—55^a of 45 pole-changer H are therefore closed, while contact 3—5 of circuit controller E and contacts 44—44^b and 55—55^b of pole-changer H are open. Lever L occupies its N position. A circuit is therefore completed for relay F over which current of 50 what I will term "normal" polarity flows from a suitable source, such as a battery G, through wires 18 and 19, NB contact 19^a of lever L, wire 24, line wire 20, wires 21 and 22, winding of relay F, wires 23 and 25, line wire 26, NB contact 27^a 55

of lever L, and wires 27 and 28 back to battery G. Relay F is therefore energized in its normal direction so that its front contact 30 and normal contact 31—31^a are closed. Since lever L occupies its N position and since contacts 44—44^a and 55—55^a of pole-changer H are closed, a circuit is also completed for relay K, and current flows from battery G through wires 18 and 19, NB contact 19^a of lever L, wire 24, line wire 20, wires 42 and 43, contact 44—44^a of pole-changer H, line wire 45, wire 46, NB contact 47^a of lever L, wires 47 and 48, winding of relay K, wires 49 and 52, NB contact 52^a of lever L, wire 53, line wire 54, contact 55—55^a of pole-changer H, wires 57 and 56, line wire 26, NB contact 27^a of lever L, and wires 27 and 28 back to battery G. Relay K is therefore energized in its normal direction. Magnet 8 is de-energized because the first circuit for this magnet is opened at contact 13^a of lever L and the second circuit for this magnet is open at contact 16^a of lever L and reverse contact 12—12^b of relay K.

In explaining the operation of the apparatus, I will first assume that it is desired to move switch A from its normal position to its reverse position. To accomplish this result, lever L is moved from its N position toward its R position. During this movement, when the lever reaches its B position, contact 13^a closes and completes the first circuit previously traced for magnet 8 so that magnet 8 becomes energized; but, as soon as the lever passes its B position, contact 13^a opens and interrupts this first circuit, so that magnet 8 again becomes de-energized. Furthermore, as soon as the lever passes its B position, contacts 27^a, 19^a, 47^a and 52^a are all opened and contact 66^a becomes closed. When contacts 27^a, 19^a, 47^a, and 52^a are opened, the circuit previously traced for relay K is opened, and when contact 66^a becomes closed, the winding of relay K is short-circuited, so that relay K becomes de-energized. Both circuits for magnet 8 are then also opened at front contact 10 of relay K, and it will be apparent, therefore, that the latch 7 is normally free to pass the projection 6^a of the segment 6. If, however, the magnet 8 should be energized for any reason, the movement of the lever will be arrested just after the lever passes its B position by engagement of the latch 7 with the projection 6^a of segment 6. When the lever reaches its D position, contact 66^a is opened, and contacts 57^a, 60^a, 50^a, 63^a, and 16^a all become closed. When contact 66^a is opened, the short circuit for the winding of relay K is removed, and when contacts 57^a, 60^a, 50^a, and 63^a become closed, another circuit for relay K is closed which passes from battery G through wires 18 and 57, RD contact 57^a of lever L, wire 58, line wire 26, wires 56 and 67, contact 55—55^a of pole-changer H, line wire 54, wire 64, RD contact 63^a of lever L, wires 63, 62 and 48, winding of relay K, wires 49 and 61, RD contact 50^a of lever L, wire 50, line wire 45, contact 44—44^a of pole-changer H, wires 43 and 42, line wire 20, wire 59, RD contact 60^a of lever L, and wires 60 and 28 back to battery G. The contacts 57^a, 60^a, 50^a, and 63^a are so arranged that the current which is supplied to relay K over this circuit is of normal polarity, and relay K therefore becomes energized in its normal direction so that its front contact 10 and normal contact 12—12^a are closed. When contacts 57^a and 60^a become closed, a circuit is also completed for relay F which passes from battery G through wires 18 and 57, RD contact 57^a of lever L, wire 58, line

wire 26, wires 25 and 23, winding of relay F, wires 22 and 21, line wire 20, wire 59, RD contact 60^a of lever L, and wires 60 and 28 back to battery G. The current supplied to relay F over this circuit is of reverse polarity, and relay F therefore opens its normal contact 31—31^a and closes its reverse contact 31—31^b. When reverse contact 31—31^b of relay F becomes closed, motor M is supplied with current from battery G through wires 18 and 57, contact 57^a of lever L, wire 58, line wire 26, wires 25 and 39, armature 1 of motor M, wire 38, asymmetric unit 40, wire 35, field 2 of motor M, wire 36, asymmetric unit 41, wire 33, contact 3—4 of circuit controller E, wire 68, reverse contact 31—31^b of relay F, wire 69, front contact 30 of relay F, wires 29 and 21, line wire 20, wire 59, contact 60^a of lever L, and wires 60 and 28 back to battery G. Motor M therefore becomes energized, and moves switch A from its normal position towards its reverse position. As soon as the switch starts to move away from its normal position, the circuit last traced for relay K is opened at contacts 44—44^a and 55—55^a of pole-changer H, and this relay is subsequently short-circuited at pole-changer H until the switch reaches its full reverse position by means of a wire 51 which is connected between two contact segments 44^c and 55^c of pole-changer H, thereby insuring that relay K will be de-energized while the switch is in transit, and thus de-energize magnet 8 so that movement of the lever L past its D position is prevented under these conditions. When the switch reaches its full reverse position, however, contacts 44—44^b and 55—55^b of pole-changer H become closed and complete another circuit for relay K which passes from battery G through wires 18 and 57, contact 57^a of lever L, wire 58, line wire 26, wire 56, contact 44—44^b of pole-changer H, line wire 45, wire 50, contact 50^a of lever L, wires 61 and 49, winding of relay K, wires 48, 62 and 63, contact 63^a of lever L, wire 64, line wire 54, contact 55—55^b of pole-changer H, wires 70 and 42, line wire 20, wire 59, contact 60^a of lever L, and wires 60 and 28 back to battery G. The current supplied to relay K over this latter circuit is of reverse polarity and relay K therefore becomes energized in its reverse direction so that its reverse contact 12—12^b becomes closed. Since contact 16^a of lever L is now closed, current is then supplied to magnet 8 over the second circuit previously traced for this magnet and magnet 8 therefore becomes energized and lifts latch 7 out of engagement with the shoulder 6^b, thereby permitting the movement of lever L to its full reverse position. When the lever L reaches its full reverse position, contact 16^a of lever L is then open and magnet 8 again becomes de-energized. Since the switch A is now in its full reverse position, the circuit previously traced for motor M is opened at contact 3—4 of circuit controller E, and motor M is therefore de-energized.

When the switch occupies its reverse position, it may be restored to its normal position by moving lever L from its R position to its N position. When the lever is moved to its D position, the magnet 8 again becomes energized due to the circuit for magnet 8 which is then closed at contact 16^a of lever L, but as soon as lever L is moved past the D position, this circuit is again opened and magnet 8 becomes deenergized. Furthermore, as soon as the lever L is moved past the D position, all circuits for relays F and K are opened, and the winding of relay K is short-circuited by contact 66^a, this winding remaining

short-circuited by this contact until just before the lever reaches its B position. As pointed out hereinbefore, when relay K is de-energized, both circuits for magnet 8 are then open at front contact 10 of relay K, and it will be apparent, therefore, that the latch 7 is normally free to pass the projection 6a when the lever is being moved from its R toward its N position. When the lever has reached the B position, the closing of contacts 27a, 19a, 47a, and 52a complete another circuit for relay K which is similar to the circuit first traced for relay K except that this circuit now includes contacts 44-44b and 55-55b of pole-changer H instead of contacts 44-44a and 44-44b of this pole-changer, so that the current supplied to relay K over this circuit is of reverse polarity. Relay K therefore again becomes energized in the reverse direction but magnet 8 now remains de-energized because one circuit for this magnet is open at contact 16a of lever L and the other circuit is opened at normal contact 12-12a of relay K. The movement of lever L is therefore arrested at the B position. Since contacts 27a and 19a of lever L are now closed, relay F again becomes energized in the normal direction and opens its reverse contact 31-31b and closes its normal contact 31-31a. A circuit for motor M is then completed from battery G, through wires 18 and 19, contact 19a of lever L, wire 24, line wire 20, wires 21 and 29, front contact 30 of relay F, wire 69, normal contact 31-31a of relay F, wire 32, contact 3-5 of circuit controller E, wire 33, asymmetric unit 34, wire 35, field 2 of motor M, wire 36, asymmetric unit 37, wire 38, armature 1 of motor M, wires 39 and 25, line wire 26, contact 27a of lever L, and wires 27 and 28 back to battery G. The current supplied to motor M over this latter circuit flows through the motor armature in the opposite direction from the current supplied to the motor over the circuit first traced for motor M, but due to the connections of the field through the asymmetric units, the current flows through the field in the same direction as before, and motor M therefore operates to restore switch A to its normal position. When the switch reaches its full normal position, contact 3-5 of circuit controller E opens, thereby interrupting the circuit last traced from motor M, and discontinuing the supply of current to the motor M. Movement of the switch A to its normal position also restores the pole-changer H to the position in which it is illustrated in the drawing, and since lever L now occupies its B position, relay K becomes energized in the normal direction over the circuit first traced for relay K. Magnet 8 therefore becomes energized and lifts the latch 7 out of engagement with the shoulder 6c of segment 6 so that the lever may then be restored to its full normal position. All parts are then restored to the positions in which they are illustrated in the drawing.

One advantage of electrical apparatus embodying my invention is that the switch operating motor may be operated in either direction in accordance with the polarity of the current supplied to a single pair of line wires 26 and 20, and that when the motor has been operated to move the switch to one position or the other, the operation of circuit controller E automatically disconnects the motor from the source of current so that power is consumed by the switch operating motor only during the actual transit of the switch.

Another advantage of electrical apparatus embodying my invention is that, since the indication 75 relay K is supplied with current over the same

pair of line wires which supply current to the switch motor, and since the supply of current to the relay is pole-changed by contacts on the lever at the same time as the current supplied to the line wires 26 and 20 is pole-changed, it will be apparent that reversals of relay K can only be caused by operation of pole-changer H. Furthermore, due to the contact 66a on lever L and to the contact member 44c and 55c of pole-changer H, relay K is short-circuited both when the lever is between the B and D positions and when the switch occupies any position between its normal and reverse position. It follows that the lever is locked against movement except when the position of the switch corresponds to the position of the lever, and this locking is accomplished without the necessity of the usual "quick-switch" customarily employed for this purpose in connection with interlocking levers used for the control of railway switches.

A further advantage of electrical apparatus embodying my invention is that since the lever may be moved freely between the B-D positions, the lever may be manipulated to successively operate the switch towards its normal and reverse positions without moving the lever to its full normal or reverse position. This operation is sometimes desirable to break lumps of coal, accumulations of ice and so forth, that prevent complete operation of the switch on the first attempt. Also, if, due to some failure the magnet 8 does not become energized when the switch position is changed, the switch may be restored to its original position and the lever moved to the corresponding end of its stroke, so that the switch may be used in one position, even though the lever may not be moved to the full position corresponding to the other position of the switch.

Although I have herein shown and described only one form of electrical apparatus embodying my invention, it is understood that various changes and modifications may be made therein within the scope of the appended claims without departing from the spirit and scope of my invention.

Having thus described my invention, what I claim is:

1. In combination, a pair of wires, a manually operable lever for reversibly supplying current to said wires, a polarized relay receiving current from the wires and arranged to be energized in one direction or the other according as said wires are supplied with current of one polarity or the other, a motor comprising two windings, a traffic controlling device controlled by the motor in accordance with the relative polarity of the currents supplied to such windings, a circuit controller actuated by said device, and means controlled by said polarized relay and said circuit controller and including asymmetric units for at times connecting the windings in series across said wires in such manner that current flows always in one direction through one winding but flows in one direction or the other through the other winding according to the position of said lever.

2. In combination, two windings, a railway switch controlled by said windings in accordance with the relative polarity of the currents flowing in said windings, a pair of line wires, means for reversibly supplying current to said wires, two contacts controlled in accordance with the position of said switch, a polarized relay receiving current from said line wires, and means controlled jointly by said polarized relay and said

- two contacts and including asymmetric units for supplying current from the wires to one winding always in the same direction and to the other winding in one direction or the other depending 5 upon the polarity of the current supplied to the wires.
3. In combination, a railway switch, a motor for operating said switch and comprising a field and an armature, two contacts controlled by said 10 switch, a manually operable lever having two positions, four asymmetric units, two line wires, means for supplying said line wires with current of one polarity when said lever occupies one position and with current of the other polarity when 15 said lever occupies the other position, a polarized relay receiving current from said line wires and having a normal contact which is closed when said wires are supplied with current of said one polarity and a reverse contact which is closed 20 when said line wires are supplied with current of said other polarity; a first circuit including said line wires, said armature, said field, two of said asymmetric units, one of said switch controlled contacts, and the reverse contact of said 25 relay; and a second circuit including said line wires, said armature, said field, the remaining two asymmetric units, the other switch controlled contact, and the normal contact of said relay.
- 30 4. In combination, a device movable between a first and a second position, a motor for operating said device and comprising two windings, a circuit controller operated by said device and having a first contact which is closed at all times 35 except when said device occupies said first position and a second contact which is closed at all times except when said device occupies said second position, two wires, a manually operable lever for reversibly supplying current to said 40 wires, a polarized relay receiving current from said wires and having a normal contact which is closed when said wires are supplied with current of one polarity and a reverse contact which is closed when said wires are supplied with 45 current of the other polarity, means for constantly connecting one terminal of one winding with one said wire, a first and second asymmetric units connected in series across the terminals of the other winding, means for constantly connecting 50 the common terminal of said first and second asymmetric units with the other terminal of said one winding, a third and fourth asymmetric units connected in series across said other winding, means including said first contact and said 55 normal contact for at times connecting the common terminal of said third and fourth asymmetric units with the other said wire, and means including said second contact and said reverse contact for at other times connecting the common terminal of said third and fourth asymmetric units with said other wire.
- 60 5. In combination, a pair of line wires, a manually operable lever, means controlled by said lever for reversibly supplying current to said line 65 wires, a railway switch movable between two extreme positions, means receiving current from said line wires for moving said switch to one extreme position or the other according as said line wires are supplied with current of one polarity or the other, a pole-changer operated by said switch, and a polarized indication relay receiving current from said line wires and controlled by said lever and said pole-changer in such manner that when the polarity of the current supplied to said line wires is reversed by said 75

lever the polarity of the current supplied to said relay remains unchanged unless said pole-changer is operated.

6. In combination, a pair of wires, a manually operable lever, means controlled by said lever for reversibly supplying current to said wires, an electric motor comprising an armature and a field, a railway switch controlled by said motor in accordance with the relative polarity of the currents flowing in said field and said armature, means for supplying current to said field from said wires always in the same direction and to said armature in one direction or the other depending upon the polarity of the current in said wires, a pole-changer controlled by said 10 switch, and an indication relay receiving current from said wires and controlled by said pole-changer and said lever in such manner that when said lever is operated to reverse the polarity of the current supplied to said wires the 15 polarity of the current supplied to said relay remains unchanged unless said pole-changer is subsequently reversed.

7. In combination, a railway switch, a manually operable lever having four positions; a pair of 25 line wires, means for supplying the line wires with current of one polarity when the lever occupies a first or a second position and for supplying the line wires with current of the other polarity when the lever occupies a third or a fourth position, means effective when the line wires are supplied with current of one polarity to move the switch to its normal position, means effective when the line wires are supplied with current of the other polarity to move the switch 30 to its reverse position, a latch for preventing movements of the lever from the second to the first position and for preventing movements of the lever from the third to the fourth position a polarized indication relay having normal and 35 reverse contacts, means controlled by said lever and by a normal contact of said polarized indication relay for releasing said latch when said lever occupies its second position, means controlled by said lever and by a reverse contact of 40 said polarized indication relay for releasing said latch when said lever occupies its third position, a pole-changer controlled by said switch, and means controlled by said lever and by said pole-changer for supplying said indication relay with current 45 from said line wires in such manner that said relay is energized in the normal direction when and only when said lever occupies its first or second position and said switch occupies its normal position but that said relay is energized in 50 the reverse direction when and only when said lever occupies its third or fourth position and said switch occupies its reverse position.

8. In combination, a railway switch; a manually operable lever having four positions, a pair 60 of line wires, means for supplying the line wires with current of one polarity when the lever occupies a first or a second position and for supplying the line wires with current of the other polarity when the lever occupies a third or a fourth position, means effective when the line wires are supplied with current of one polarity to move the switch to its normal position, means effective when the line wires are supplied with current of the other polarity to move the switch 65 to its reverse position, a latch for preventing movements of the lever from the second to the first position and for preventing movements of the lever from the third to the fourth position, a polarized indication relay having normal and 70 reverse contacts, means controlled by said lever and by a normal contact of said polarized indication relay for releasing said latch when said lever occupies its second position, a pole-changer controlled by said switch, and means controlled by said lever and by said pole-changer for supplying said indication relay with current 75 from said line wires in such manner that said relay is energized in the normal direction when and only when said lever occupies its first or second position and said switch occupies its normal position but that said relay is energized in the reverse direction when and only when said lever occupies its third or fourth position and said switch occupies its reverse position.

reverse contacts, a first contact on said lever arranged to be closed when and only when said lever occupies its second position, a second contact on said lever arranged to be closed when

- 5 and only when said lever occupies its third position, means controlled by a normal contact of said polarized indication relay and said first contact for at times releasing said latch and by a reverse contact of said polarized indication relay
- 10 and said second contact for at other times releasing said latch, a pole-changer controlled by said switch, and means controlled by said lever and by said pole-changer for supplying said indication relay with current from said line wires
- 15 in such manner that said relay is energized in the normal direction when and only when said lever occupies its first or second position and said switch occupies its normal position and that said relay is energized in the reverse direction when
- 20 and only when said lever occupies its third or fourth position and said switch occupies its reverse position.

9. In combination, a railway switch; a manually operable lever having four positions; a pair 25 of line wires, means for supplying the line wires with current of one polarity when the lever occupies a first or a second position and for supplying the line wires with current of the other polarity when the lever occupies a third or a fourth position, means effective when the line wires are supplied with current of one polarity to move the switch to its normal position, means effective when the line wires are supplied with current of the other polarity to move the switch 30 to its reverse position, a latch for preventing movements of the lever from the second to the first position and for preventing movements of the lever from the third to the fourth position, a polarized indication relay having normal and 35 reverse contacts, a first contact on said lever arranged to be closed when and only when said lever occupies its second position, a second contact on said lever arranged to be closed when and only when said lever occupies its third position, means controlled by a normal contact of said 40 polarized indication relay and said first contact for at times releasing said latch and by a reverse contact of said polarized indication relay and said second contact for at other times releasing said latch, a pole-changer controlled by said switch, means controlled by said lever and by said pole-changer for supplying said indication relay with current from said line wires in such 45 manner that said relay is energized in the normal direction when said lever occupies its first or second position and said switch occupies its normal position but that said relay is energized in the reverse direction when said lever occupies its third or fourth position and said switch occupies its reverse position, and means controlled 50 by said lever for short circuiting the winding of said indication relay when said lever is between said second and said third position.

10. In combination, a pair of wires, means for 55 reversibly supplying current to said wires, an electric motor comprising two windings and capable of rotation in one direction or the other depending upon the relative polarity of currents flowing in said windings, a polarized relay receiving current from said wires, and means controlled by said polarized relay and including asymmetric units for supplying current from said wires to one of said two windings always in the same direction and to the other of said two 60 windings in one direction or the other depending

upon the polarity of the current supplied to said wires.

11. In combination, two windings, a device controlled by said windings and capable of assuming one condition or another depending upon the relative polarity of currents flowing in said windings, a pair of wires, means for reversibly supplying current to said wires, a polarized relay receiving current from said wires, and means controlled by said polarized relay and including 10 asymmetric units for supplying current from said wires to one winding always in the same direction and to the other winding in one direction or the other depending upon the polarity of the current supplied to said wires. 15

12. In combination, an electro-responsive device comprising two windings and capable of assuming one condition or another depending upon the relative polarity of currents flowing in said windings, two wires, manually operable means for 20 reversibly supplying current to said wires, means for constantly connecting one terminal of one winding with one said wire, a first and a second asymmetric unit connected in series across the terminals of the other winding, means for constantly connecting the common terminal of said first and second asymmetric units with the other terminal of said one winding, a third and a fourth asymmetric unit connected in series across said other winding, and means for at times connecting the common terminal of said third and fourth asymmetric units with said other wire. 25

13. In combination, a device movable between two extreme positions, a pair of wires, means for 30 reversibly supplying current to said wires from a given source, other means receiving current from said source over said wires for operating said device from one extreme position to the other according as said wires are supplied with current of one polarity or the other, and indication means 35 responsive to the polarity of current received from said source over said wires and controlled jointly by said means and said device in such manner that the polarity of the current received by said indication means remains unchanged 40 when the polarity of the current supplied to said wires is reversed by said means unless said device has been operated. 45

14. In combination, a device movable between two extreme positions, a pair of wires, means for 50 reversibly supplying current to said wires from a given source, other means receiving current from said source over said wires for operating said devices from one extreme position to the other according as said wires are supplied with 55 current of one polarity or the other, a pole-changer operated by said device, and indication means responsive to the polarity of the current received from said source over said wires and controlled jointly by said means and said pole-changer in such manner that the polarity of the current received by said indication means remains unchanged 60 when the polarity of the current supplied to said wires is reversed by said means unless said pole-changer has been operated. 65

15. In an indication system for railroads, a polarized line circuit, a traffic controlling device 70 remotely controlled over said polarized line circuit, and means indicating the condition of said traffic controlling device including a polarized indication circuit receiving potential from said polarized line circuit, and means in the polarized indication circuit compensating for a change in polarity of said polarized line circuit.

16. In an indication system, a source of po- 75

- 5 tential, a plurality of pole changing means, an indication device responsive to a reversal of direction in current flow, and means connecting said device to said source of potential through
5 said plurality of pole changing means in series, whereby operation of an odd number of pole changing means reverses direction of current flow in said device, and whereby operation of an even number of pole changing means does not reverse
10 the direction of current flow in said device.
17. In a control system for railroad track switches, a track switch, a switch machine for operating said track switch, point detector contacts jointly operated by said track switch and
15 said switch machine, manually operable control and indication contacts, a source of potential, a control relay for governing said switch machine, a circuit for said control relay from said source of potential through said control contacts, an
20 indication relay, a circuit for said indication relay from said source of potential through said control contacts, said point detector contacts and said indication contacts respectively in series, and circuits selected by said indication relay.
- 25 18. In an interlocking system, a control lever having control and indication contacts, a power-operated track switch, a control circuit for said power-operated track switch governed by said control contacts, point detector contacts operated
30 in accordance with the response of said power-operated track switch, an electro responsive indicating device, an indication circuit for said electro responsive indicating device connected to said control circuit through said point detector contacts and said indication contacts, and circuits selected by said electro responsive indicating device.
- 35 19. In combination, a source of electrical potential, a control relay, an indication relay, means connecting said control relay and said indication relay successively in multiple with said source of electrical potential, means selectively reversing the polarity only with respect to said control relay, and means selectively reversing the polarity only with respect to said indication relay.
- 40 20. In a traffic controlling system, the combination with a central office and a distant way station, a line circuit connecting said office and way station, two polarity energy applying means and a polar relay at said office, means for including either said energy applying means or said polar relay in said circuit and for including said polar relay in a particular polar direction in said circuit in accordance with the last polarity of current applied to said line circuit by said energy applying means, and means at said way station controlled by said energy applying means and for controlling said polar relay over said line circuit.
- 45 21. In a traffic controlling system, the combination with a central office and a distant way station, a line circuit connecting said office and way station, two polarity energy applying means and a polar relay at said office, means for including either said energy applying means or said polar relay in said circuit and for including said polar relay in said circuit in accordance with the last polarity of current applied to said line circuit by said energy applying means, and means at said way station controlled by said energy applying means and for controlling said polar relay over
50 said line circuit.
- 55 22. In a traffic controlling system, the combination with a central office and a distant way station, a line circuit connecting said office and way station, two polarity energy applying means and a polar relay at said office, means for including either said energy applying means or said polar relay in said circuit and for including said polar relay in a particular polar direction in said circuit in accordance with the last polarity of current applied to said line circuit by said energy applying means, and traffic controlling means at said way station controlled by said energy applying means and including means for controlling said polar relay in accordance to the operated condition of said traffic controlling means.
- 60 23. In combination, means for controlling a switch machine in accordance with the polarity of current of a particular character transmitted over a line circuit from a central office and for transmitting an indication to said central office by current of the same character over said line circuit and having a polarity corresponding to the position of said switch machine.
- 65 24. In combination, a railway track switch, a pole-changer operated in conjunction with said switch and arranged to occupy a normal or a reverse position according as said switch is in its normal or its reverse position, a manually operable lever having normal and reverse contacts closed when said lever is moved to a normal or a reverse position respectively, normal and reverse control circuits for said switch including said normal and reverse lever contacts respectively, means controlled by said normal and reverse control circuits for operating said switch to normal and reverse positions, indication means for indicating the normal and reverse positions of said switch, and normal and reverse control circuits for said indication means controlled by said pole-changer and including said normal and reverse lever contacts respectively.
- 70 25. In combination, a railway track switch, manually controlled normal and reverse switch circuits for controlling operations of said switch to normal and reverse positions respectively, indication means selectively responsive to current of normal and reverse polarities for indicating normal and reverse positions of said switch, and manually controlled normal and reverse indication circuits for energizing said indication means by current of normal and reverse polarities controlled by said switch in normal and reverse positions respectively and supplied from said manually controlled normal and reverse circuits.
- 75 26. In combination, a railway track switch, control apparatus selectively responsive to current of normal and reverse polarities for controlling operations of said switch to normal and reverse positions respectively, indication means selectively responsive to current of normal and reverse polarities controlled by said switch for indicating normal and reverse positions respectively of said switch, and manually controllable means for supplying current of normal and reverse polarities for energizing said control apparatus and for energizing said indication means through pole-changing means controlled by said switch.
- 80 27. In combination, a railway track switch, control apparatus selectively responsive to current of normal and reverse polarities for controlling operations of said switch to normal and reverse positions respectively, a manually controllable device, circuits controlled by said manually controllable device for energizing said control
- 75

apparatus by current of normal or reverse polarity according as said manually controllable device is in a first or a second position, indication means selectively responsive to current of normal and reverse polarities for indicating normal and reverse positions respectively of said switch, and circuits controlled by said manually controllable device and by said switch for energizing said indication means by current of normal or reverse polarity according as said switch is in the normal or the reverse position but independently of the position of said manually controllable device.

28. In combination, a railway track switch, a normal control wire and a reverse control wire for said switch, means located at a remote point for

connecting one or the other of said wires with one terminal of a source of current, a polarized indication relay, and means operating when said switch is in normal position to connect one terminal of the winding of said relay with said one terminal of said source through said normal wire and the other terminal of the relay winding with the other terminal of said source, said means operating when the switch is in reverse position to connect the second terminal of said relay winding with said one terminal of said source through said reverse wire and the first terminal of the relay winding with said other terminal of said source.
